WILLIAM C. HEDGCOCK, OF CHICAGO, ILLINOIS, ASSIGNOR TO AMERICAN STEEL
FOUNDRIES, OF CHICAGO, ILLINOIS, A CORPORATION OF NEW JERSEY.

REVERSIBLE-FULCRUM ARRANGEMENT.

1,425,649.

Specification of Letters Patent. Patented Aug. 15, 1922.

Application filed August 8, 1921. Serial No. 490,497.

To all whom it may concern:

Be it known that I, WILLIAM C. HEDGCOCK, a citizen of the United States, residing at Chicago, in the county of Cook and State 5 of Illinois, have invented certain new and useful Improvements in Reversible-Fulcrum Arrangements, of which the following is a specification:

This invention relates to a reversible fulcrum arrangement and is a modification of that shown in my co-pending application, Serial Number 459,790, filed April 8, 1921.

One object of my invention is to provide a one piece reversible fulcrum which is simple and durable in construction, efficient in operation and adapted to meet all the requirements for successful commercial use.

Another object is to provide a simple and efficient locking connection between the compression member of a brake beam and a fulcrum.

These and other objects are accomplished by means of the arrangement disclosed on the accompanying sheet of drawings, in 25 which—

Figure 1 is a top plan view of a brake beam and fulcrum embodying my invention;

Figure 2 is a fragmentary rear elevation of the intermediate part of a brake beam 30 and the rear of the fulcrum;

Figure 3 is a fragmentary top plan view of the same arrangement;

Figure 4 is a fragmentary side elevation of the fulcrum showing the compression 35 member of the brake beam in section; and

Figure 5 is a sectional view taken in the plane of line 5—5 of Figure 4.

The invention is illustrated in connection with a brake beam of the trussed type having a compression member 10, a tension member 11 and my improved reversible fulcrum 12 interposed therebetween. The rear end of the fulcrum 12 is provided with a banded portion 13 which surrounds or 40 braces the compression member 10, the upper and lower portions of the band 13 having V-shaped walls 14 and 15 for respectively engaging the upper and lower flanges 16 and 17 of the compression member for limiting 45 the reversible movements of the reversible fulcrum 12. In this particular instance a rear wall 18 of the band 13 is pivotally connected to the web 19 of the compression member by a rivet 20, but any other suitable 50 pivotal connection may be used.

It is desirable to provide means which

will firmly clamp and lock the reversible fulcrum in its different operative positions with respect to the compression member. To this end the rear end of the main portion of the 60 fulcrum 12 is provided with a projection 21 extending rearwardly toward the web or rear wall 19 of the compression member. This projection has formed at its sides, or is bounded by inclined wedge-ways 22, 23, 24 65 and 25, leaving the main projection 21 extending outwardly beyond said wedge-ways. These wedge-ways are arranged in a diamond shape, the wedge-ways 22 and 23 having their highest portions at the right 70 hand ends thereof and the wedge-ways 24 and 25 having their highest portions at the upper ends thereof as viewed in Figure 5. Co-operating with the wedge-ways and with the compression member for securing and 75 locking the fulcrum to the compression member, a wedge-key 26 is provided. This wedge-key has a main web portion 27 which, at one end, terminates in a head 28 and at the other end in two tongues 29 and 30, 80 which tongues when the wedge-key is driven home may be bent over into a position for locking the wedge-key against accidental removal. At the upper and lower edges of the wedge key there are formed wedge-shaped flanges 31 and 32 which, when the wedge is 85 in wedging and locking position, occupy the wedge-ways 22 and 23 with the inner surfaces of the wedges 31 and 32 engaging the adjacent side walls of the wedge-ways 22 90 and 23 or of the projection 21. These wedge shaped flanges 31 and 32 when in securing position engage the floor of the wedge-ways 22 and 23 and also the inner edges of the flanges 16 and 17 of the compression member. On the opposite side of the main web 95 27 of the wedge-key 26 flanges 33 and 34 are provided which engage the flanges 16 and 17 of the compression member and co-operate with the wedge-shaped flanges 31 100 and 32 for positively locking the fulcrum in either of its two operative positions.

To reverse the fulcrum it is merely necessary to straighten out the tongues 29 or 30 and withdraw the wedge-key. It will be 105 understood that when the fulcrum is locked in a position reversed from that shown in the figures of the drawings, the wedge shaped flanges 31 and 32 of the wedge-key 26 will occupy wedge-ways 24 and 25 of the 110 fulcrum.

The front end of the fulcrum 12 is pro-

vided with two fingers 35 which are shaped and spaced from each other in a manner to permit the fulcrum to be reversed without any binding action between the fulcrum and the tension rod 11.

It is my intention to cover all modifications of the invention herein disclosed which do not depart from the spirit and scope of the following claims.

10 I claim:

1. An integrally formed reversible brake beam fulcrum including a banded end for the reception of a compression member, the front wall of said banded portion having a projection bounded by inclined wedge-ways, and a wedge-key having flanges co-operable with said wedge-ways and the compression member for locking the fulcrum in its different operative positions.
- 20 2. An integrally formed reversible brake beam fulcrum including an end portion for embracing a compression member, the front wall of said embracing portion having a projection at the sides of which inclined wedge-ways are formed, and a wedge-key having wedge-shaped flanges co-operable with said wedge-ways and the compression member for securing the fulcrum in its different operative positions.

3. An integrally formed reversible brake beam fulcrum including an end portion for embracing a compression member, the front wall of which portion having a projection with inclined wedge-ways extending rearwardly from the end of the projection, and a wedge-key having wedge-shaped flanges occupying said wedge-ways and adapted to wedge in between the fulcrum and portions of the compression member for securing the fulcrum in its different operative positions. 40

4. An integrally formed reversible brake beam fulcrum including an end portion for embracing a compression member, the front wall of which portion having a projection with inclined wedge-ways extending rearwardly from the end of the projection, and a wedge-key having wedge-shaped flanges occupying said wedge-ways and adapted to wedge in between the fulcrum and portions of the compression member for securing the 50 fulcrum in its different operative positions, said wedge-key also having flanges associated with the compression member co-operating to lock the fulcrum in its different operative positions. 55

Signed at Chicago, Illinois, this 2nd day of August, 1921.

WILLIAM C. HEDGCOCK.
